DISPENSING NOZZLE

Frederick H. Valiton, Deer Lodge, Mont.

Application June 10, 1940, Serial No. 339,771

2 Claims. (Cl. 226—120)

The present invention relates to dispensing nozzles and more particularly to gasoline dispensing nozzles.

The primary object of the invention resides in the provision of a nozzle construction including valve means for preventing overfilling of a receptacle, such as a gasoline tank when being filled by gasoline dispensed through the nozzle, said valve means being automatically closed when the liquid reaches a predetermined level in the tank.

Another object of the invention resides in the provision of a nozzle of this character in which means are provided for permitting the escape-
ment of air from within a tank being filled by a liquid discharged through the nozzle whereby a complete filling of the tank is assured without liability of the tank overflowing due to the tank becoming air bound.

A still further object of the invention resides in the provision of a gasoline, or the like, dispensing nozzle having associated with the discharge end thereof a valve which will automatically stop the flow of gasoline or other liquid when the supply within the container being filled submerges the end of the dispensing nozzle.

The invention also consists in certain other features of construction and in the combination and arrangement of the several parts, to be hereinafter fully described, illustrated in the accompany drawing and specifically pointed out in the appended claims.

In describing my invention in detail, reference will be had to the accompanying drawing wherein like characters denote like or corresponding parts throughout the several views, and in which:

Figure 1 is a vertical sectional view of a dispensing nozzle embodying the features of the present invention.

Figure 2 is a partial vertical sectional view illustrating the position of the various parts when the nozzle is closed.

Figure 3 is a longitudinal sectional view taken substantially on line 3—3 of Figure 1.

Figure 4 is a perspective view of a disc formed with a ratchet tooth adapted to be engaged for holding the valve in the nozzle in open position.

Figure 5 is an elevational view of the cam employed for maintaining the valve in the nozzle open.

Referring to the drawing for a more detailed description in which like parts are designated by the same numerals in the several views, the numeral 6 generally designates the usual rigid type of spout employed with a flexible hose of a

gasoline pump, the same being coupled by means of the bushing 7 with a filler valve, not shown. As is well known, the filler valve is mounted in the hose connection adjacent the nozzle end thereof and is adapted to be actuated by the operator when dispensing gasoline.

The end of the filler spout 6 is enlarged as indicated at 8 and internally threaded as indicated at 9. A tube 10 is threadedly attached to the inside of the filler spout 6, the end of said tube being seated within the spout, as shown in Figure 1 of the drawing, to prevent leakage around the connection. A pair of arms 11 extend inwardly of the tube 10 and are united to a collar 12, said collar forming a guide for the stem 13 of the check valve 14. The arms 11 form a seat 15 for the valve 14 and when said valve is in closed position, as shown in Figure 2 of the drawing, liquid is prevented from being discharged from the spout. A collar 16 is attached to the lower end of the stem 13 and between said collar and the guide 12 there is mounted a coil spring 17, said coil spring aiding in returning the valve to closed position upon its seat 15. The lower end of the tube 10 is reduced in diameter as indicated at 18, which end is adapted to be inserted within the neck 19 of the tank 20.

A skirt 21 partially surrounds the tube 10 and is attached thereto by any desired means as indicated at 22. A shaft 23 has one end journaled at 24 within the tube 10, the other end of said shaft projecting beyond the skirt 21 and has attached thereto a knurled disc 25. A cam 26 is fixedly secured to the shaft 23 and is disposed directly beneath the collar 16 of the valve stem 13 whereby rotation of said shaft will bring said cam into contact with the collar 16 for raising the valve from its seat against the tension of the spring 17. A threaded packing nut 27 surrounds the shaft 23 on the outside of the tube 10 for preventing leakage around said shaft.

Extending from the tube 10 and within the skirt 21 are a pair of arms 28 and 29, respectively, attached to the tube by any desired means as indicated at 30. The arm 28 is longer than the arm 29 and has its end 31 bent at right angles to form a stop for the disc 32 secured to the shaft 23 and adapted to rotate therewith upon rotation of the knurled disc 25. A pair of pins 33 project laterally of one face of the disc 32 for contact with the end 31 of the arm 28 for limiting rotation of said disc. The arm 29 has pivotally connected thereto as indicated at 35 a substantially L-shaped pawl 36 adapted to engage

the projection 36 formed on the disc 32 for locking said disc in position. A coil spring 37 surrounds the shaft 23 and has one end secured thereto as indicated at 38 with its other end attached, as indicated at 39, to the arm 29. The spring 31, when assembling the device, is wound with sufficient torque to operate the valve 14, which action will be hereinafter more fully described.

Attached to or formed integral with the reduced end 18 of the tube is a substantially cylindrical-shaped head 40, the bottom end of the skirt 21 resting upon said head as shown in Figure 1 of the drawing. The head 40 is formed with a chamber 41 which entirely surrounds the tube 10 and a second chamber 42 which is separate and apart from the chamber 41 for a purpose to be hereinafter described. Extending upwardly from the head 40 within the skirt 21 is a cylinder 43 having communication with the chamber 42. The upper end of the cylinder is closed by means of a cap 44 formed with a central opening 45 and apertures 46 for permitting the escapement of air as the piston is moved upwardly through the cylinder 43. A piston 47 mounted on a rod 48 reciprocates within the cylinder 43 being operated by the escapement of air from the tank through the chamber 42. As the piston 47 and rod 48 are moved upwardly, the rod 48 will contact the pawl 35 for releasing the same from the ratchet 36 of the disc 32. As the disc is released, the tension of the spring 37 will rotate the shaft 23 substantially 180° or until one of the pins 33 contacts the arm 28 to rotate the cam 26. As the cam is rotated the valve 14 is urged downwardly by means of the spring 17 into engagement with its seat 15. A U-shaped spring 49 is attached to the arm 29 and is adapted to be compressed when the piston rod 48 pushes upwardly on the pawl 35, said spring returning the pawl to normal position as the piston moves downwardly within its cylinder.

A resilient gasket 50 is carried by the head 40 and normally contacts the end of the neck 19 of the tank 20 when filling the tank 20, said gasket being protected by means of the annular continuation 60 and 61, respectively, of the head 40. The head 40 and gasket 50 are of a suitable diameter to fully cover various sized gasoline tank necks. The gasket 50 is also of suitable thickness so that the operator does not have to use undue care in placing the same in a horizontal plane with the top of the neck 19 in order to have a tight joint.

Extending from the chamber 41 is a tubular passage 51, said passage communicating with the chamber 41 and terminating in the wall of the skirt 21. The passage 51 permits the escapement of air from the chamber 41, said air being expelled while filling the tank. Air from the tank is carried to the chamber 41 through the medium of a segmental-shaped pipe 52, said pipe terminating in close proximity to the submerged end of the tube 10 and forming a passageway 53 having communication with the chamber 41. Air being expelled from the tank will be discharged through the passage 53 into the chamber 41 and out through the passage 51 until the tank has been filled and the lower end of the pipe 52 completely submerged in the gasoline. The remaining air within the neck of the tank will be compressed in the chamber 42 and cylinder 43 as will be hereinafter described.

In the operation of the device, the operator when instructed to dispense a quantity of gaso-

line into the tank 20 will insert the end of the tube 10 within the neck 19 of the tank until the gasket 50 is seated upon the end of the neck. The knurled disc 25 is rotated clockwise until one of the pins 33 contacts the arm 28. Turning the disc 25 will, of course, rotate the shaft 23 and at the same time wind the spring 37 a half turn, and as the disc 25 is rotated substantially 180° in a clockwise direction, the end of the pawl 35 will engage the notch 36 of the disc 32 thereby preventing counter-clockwise rotation of the discs and shaft. When rotating the disc 25 and shaft 23, the cam 26, being locked to the shaft 23, will rotate with the same lifting the valve 14 from its seat 15 against the tension of the spring 17. The position of the several parts when lifting the valve is shown in Figure 1 of the drawing. If desired, the face of the disc 25 can be suitably marked for indicating the "open" and "shut" positions of the valve 14. With a slight pressure now exerted downwardly on the resilient gasket 50, the operator opens the usual gasoline filler valve, not shown, and the gasoline is dispensed through the nozzle 6, tube 10 and into the tank 20. As the gasoline rises in the tank the air from within the tank is expelled into the chamber 41 of the head 40 through the segmental-shaped pipe 52. The position of the pipe 52 is such that nothing but dry air will be discharged therethrough. The air from the chamber 41 is then expelled to the atmosphere through the tubular passage 51. An uninterrupted flow of gasoline will be discharged into the tank and when the flow of the gasoline reaches the level indicated at 55, which is the top of the tank 20, air will be displaced at a higher velocity and when the gasoline has reached the level indicated at 56, the end of the segmental-shaped pipe 52 will be submerged thereby precluding further expulsion of air. This sudden compression of air will then be compressed in the opening 57 and chamber 42 urging the piston 47 upwardly against the tension of the spring 54 until the rod 48 contacts the pawl 35 to release the same from the disc 36. The spring 37 will then rotate the shaft 23 in a counter-clockwise direction until a pin 33 abuts the arm 28. This action will release the cam 26 from the valve 14 permitting said valve to be returned to its seat or to a closed position shutting off the flow of gasoline before it can rise any higher in the neck 19. When the operator notes the movement of the disc 25 and feels the jar of the valve 14 closing, it is his signal that the tank has been filled. He then releases the lever of the usual filler valve shutting off the flow of gasoline from the pump. The action of the piston 47 to release the pawl 35 and the spring 37 for rotating the shaft 23 in a counter-clockwise direction to close the valve 14 is sufficiently rapid to prevent the overflow of gasoline from the neck 19. In other words, the device is designed to operate before any material quantity of pressure has had time to accumulate in the neck of the tank. Therefore, the seams of the tank are not subjected to prohibitive pressure and the lower pressure enables the operator to easily hold the resilient gasket 50 in position on the neck of the tank. There is also eliminated the possibility of any air locks being formed in the tank or the neck of the tank during the filling operation.

The chamber 41 in addition to forming a means for permitting the escapement of air from within the tank, acts as a reservoir when the lower

end of the tube 52 becomes submerged. Gasoline rising within the neck 19 will flow through the opening 53 into the reservoir 41 but before displacement through the opening 51 takes place, the valve 14 will be seated. Thus the chamber 41 allows the valve 14 time to act and the bevelled surface 41' allows any gasoline contained therein to drain back into the tank through the opening 53.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In a device of the class described, comprising a liquid supply nozzle, a tube extending from said nozzle adapted to be inserted into a container for directing the flow of liquid therein, a valve seat formed in said tube, a check valve supported on said seat, a shaft extending transversely of said tube, one end of said shaft projecting beyond said tube, a cam mounted on said shaft adapted to contact said valve for raising the same from its seat, a knurled disc on the projecting end of said shaft adapted to be manually operated for rotating said shaft and cam, a second disc mounted on said shaft between said tube and said first mentioned disc, pins projecting laterally from one face of said second disc, an arm attached to said tube above said shaft having its free end bent for contact with said pins for limiting rotation of said shaft, a second arm attached to said tube below said shaft, a spring

pressed pawl pivotally attached to said second arm, one end of said pawl adapted to engage said second disc upon rotation thereof to lock said valve in raised position, a cylindrical-shaped member surrounding said tube for contact with a portion of said container, a pair of non-communicating chambers formed in said member, a tube communicating with one of said chambers and terminating within said container forming a passage for air being expelled therefrom, a cylinder communicating with the other chamber and supported above said member, and a piston and rod within said cylinder adapted to be operated by air from said chamber to effect engagement of said rod with said pawl for returning said shaft and valve to normal position upon a predetermined level of liquid being reached within said container.

2. In a device of the character described, comprising a liquid supply nozzle, a tube attached to and extending from said nozzle for insertion into a container, a valve seat formed in said tube, a spring closed check valve cooperating with said seat, a stem carried by the check valve, a shaft extending transversely of said tube, one end of the shaft projecting beyond the tube, a cam mounted on said shaft adapted to contact with the valve stem for raising said valve from its seat, a coil spring surrounding the shaft and having one end connected thereto and the other end connected to the tube, a disc carried by the shaft with projections on its outer periphery, an intermediate pivoted latch adapted to engage the projections on the disc for holding the shaft in its rotated position against the tension of the coil spring, a handle on the outside of the tube for rotating the shaft, and a pressure operated plunger adapted to engage the end of the intermediate pivoted latch, whereby the shaft is released and rotated to cause the cam to disengage the valve stem to allow the valve to be seated.

FREDERICK H. VALTON.
